DAVID BOURQUE, OF AMESBURY, MASSACHUSETTS, ASSIGNOR TO G. W. J. MURPHY CO.,
OF MERRIMAC, MASSACHUSETTS, A CORPORATION OF MASSACHUSETTS.

STUD-AND-SOCKET FASTENER.

1,292,574.

Specification of Letters Patent. Patented Jan. 28, 1919.

Application filed July 14, 1916. Serial No. 109,379.

To all whom it may concern:

Be it known that I, DAVID BOURQUE, a subject of the King of Great Britain, and a resident of Rocky Hill, Amesbury, in the 5 county of Essex and Commonwealth of Massachusetts, have invented an Improvement in Stud-and-Socket Fasteners, of which the following description, in connection with the accompanying drawings, is a specification, like characters on the drawings representing like parts.

This invention relates to that class of stud-and-socket fasteners in which the socket is provided with yielding jaws to receive and lock over the head of the stud. My invention provides a fastener of this type suitable for almost universal use as a snap fastener, but particularly adapted for use on vehicle curtains, and the like, where it is 10 essential that the curtain carrying the socket be so securely attached to the stud that it will not be disengaged therefrom by the flapping of the curtain or an outward strain thereon due to wind pressure. A fastener 15 constructed in accordance with my invention is more convenient to apply and use than those hitherto known, and also has superior holding power.

My invention will best be understood by 20 reference to the following description of an illustrative embodiment thereof, taken in connection with the accompanying drawing showing the same, wherein:

Figure 1 is a central sectional view of the 25 fastener;

Fig. 2, a similar view showing the stud member tilted and in position to be detached from the socket member;

Fig. 3, a sectional view on the line 3—3 of 30 Fig. 1; and

Fig. 4, a face view of the socket member.

Referring to the various parts by numerals, the form of fastener shown includes the stud member 1, which is adapted to be secured to a curtain 2, or to a rigid support. This stud may be secured in position in any suitable manner, and may be formed with the cylindrical body part 3 having a reduced neck portion 4 near its outer end, the said 45 reduced neck merging into the cylindrical body part along a curved cam-like surface 5. At the outer end of the reduced part 4 is formed the head 6, said head having an inner square face 7 perpendicular to the axis 50 of the stud. This square face preferably

is merged into the dome-like head 6 through the rounded corner 8, so that there is no sharp edge between the curved surface of the head and the square or straight surface of the face 7. The diameter of the head at 60 its point of greatest width may be substantially equal to the diameter of the cylindrical body part 3 of the stud. The rounded corner 8 and the cam-like surface 5 serve materially in assisting in opening the jaws 65 of the socket member, as will be more fully hereinafter set forth. It should be noted that the neck 4 is substantially co-axial with the shank or head, or, in other words, is uniformly reduced on every side, and that 70 the stud is therefore perfectly symmetrical.

The socket member shown herein consists of a circular casing or eyelet 10, having a front outer wall 11 and a short cylindrical wall 12. At the inner end of the cylindrical 75 wall is formed a short annular flange 13, said flange forming a radial internal shoulder 14. At the outer end of the radial flange 13 is formed a cylindrical portion 15. Within this cylindrical portion, and bearing 80 against the shoulder 14, is a washer 16, the purpose of which is to retain in position the spring jaws of the socket as hereinafter described, said washer having a central aperture 17 formed therein. Between the front 85 wall 11 of the socket member and the washer 16 are arranged the spring locking jaws, the cylindrical wall 12 being of sufficient length to form a narrow space or jaw-receiving chamber, in which the jaw structure fits. 90

The jaw structure consists of a number of segmental members 18, preferably three, which fit together and form an annulus. In other words, the parts 18 are truncated circular sectors. Each member 18, at its 95 inner edge, may be bent inwardly to form the inwardly extending, curved wall 19, said walls of all the members forming the wall of a cylindrical cup when said members are in their normal positions, as shown in Figs. 100 3 and 4. At the inner edges of the curved walls 19, the members are bent parallel with the main portions thereof, to form the annular locking flange 20. Suitable spring means are provided normally to hold the 105 members 18 together, and I have shown herein each locking member formed with an inwardly extending lug 21, and, engaging the outer edges of these lugs and maintaining the locking members in their normal 110

locking position, a split spring ring 22, shown clearly in Fig. 3. Each of said jaw members 18 is free to move radially outwardly against the constructive tension of the split spring ring, in response to an outward pressure brought thereon by the head of the stud member when the said member is being attached to or detached from the socket member.

10 The construction of the jaw members from a split annulus in this manner is simple and inexpensive. The various segments formed will fit together like the blocks or voussoirs of an arch, and the structure will thus, to a great extent, maintain itself in shape, and, when constricted by the split spring ring 22, is substantially indeformable. The structure itself is symmetrical and the forces developed when the jaws are forced apart are distributed substantially equally about the circumference. In other words, the several sectors 18 yield outwardly substantially along radial lines, the action being quite different from that of a jaw structure which opens at one end and may be wedged apart in such a way as to let the coöperating stud escape at one side when it would be held at the other.

15 20 25 30 35 40 45

While any suitable number of sectors 18 may be used, I preferably limit the number to three, as here shown. The reason for this is that three will form a trussed frame which cannot be distorted apart from actual bending or breaking of the sides, whereas a polygon of four or more sides may be changed in shape without altering the sides themselves. For example, a square can be collapsed, as it were, into an oblique parallelogram. A triangle, on the other hand, permanently retains its shape, and all trussed frames in houses, bridges and the like are formed of a number of triangles joined together. By limiting the number of segments to three, therefore, the firmness of the whole jaw structure is enhanced and the forces are better distributed.

The socket may be secured in position in any suitable manner, but I preferably utilize a tubular rivet 24, having a large flange 23 fitting against the washer 16, said rivet being secured in position by an annular in-turned flange 25, said flange also serving permanently to secure the washer 16 in position against the shoulder 14. The tubular rivet extends through an aperture in the curtain 26, and its inner end is turned outwardly and bent over the clenching washer 27. The washer and the turned-over portion of the rivet clench and lock the curtain against the flange 23 of the tubular rivet, and against the inturned flange 25 of the socket casing. By this means the curtain material is clenched and locked to the socket member. The stud member enters the socket member through the tubular rivet

and passes through the aperture 17 in the spring-retaining washer.

I preferably utilize the separate washer 16 as shown in the drawings, as by so doing I can provide a chamber closely fitting the 70 jaw structure and extending down toward the center so as to afford the same ample support and yet one in which the jaw structure has ample freedom of play. The tubular rivet 24 may then be arranged so that 75 the flange 23 thereof merges into the tubular part at a considerable distance from the center and along a curve as shown. Consequently, when the other end of the rivet is turned down over the washer 27, the shocks 80 will be transmitted along the more or less conical surface formed where the rivet is bent, and there will be no tendency for the same to be jammed down and pinch the jaw structure against the front wall 11 of the 85 casing. On the contrary, the structure is neatly housed in the chamber formed by this casing and the washer 16.

When the stud member is engaged with the socket member the head of the stud rests 90 in the cylindrical cup formed by the walls 19 of the locking jaws, and the locking flanges 20 fit against the face 7 of said head, the edges of said locking flanges fitting close to the reduced portion 4 of the stud. As 95 the said locking flanges fit squarely against the square face of the shoulder 7, the two members of the fastener cannot be separated by a direct outward pull on the socket, or by a direct inward pull on the stud member. 100 When it is desired to separate the two members, one or the other of said members must be tilted or inclined with respect to the other. This movement will cause the rounded portion 8 of the head of the stud to 105 impinge against the wall 19 of one of the locking jaws, and to force said jaw radially. When the tilting movement has been sufficient to bring the cam-like surface 5 of the stud member against the jaw member on the 110 opposite side of the center thereof from that portion of the head which is in engagement with the wall 19 of one of the jaw members, the said cam-like portion of the stud will assist in separating the jaws to permit the head 115 to be withdrawn from the jaws, as shown in Fig. 2 of the drawing. This result may be secured by a relative tilting or angular movement of the stud and socket members, without regard to the direction of movement of 120 the tilted part. This is of great advantage for the reason that it permits the fasteners to be secured in place in any desired relation to each other, it being only necessary that they be so placed that the stud may be 125 caused to enter the socket through the tubular rivet.

It is apparent from the above description that an important feature of my device is the symmetrical construction thereof. This is 130

of considerable importance when the fasteners are placed in position, as it is unnecessary to take into account the angular position thereof but only to provide for their registration with the studs 3. When it is desired to place a row of fasteners along the curved edge of a curtain, for example, a considerable source of difficulty is at once obviated. This symmetrical formation is 10 also important in that it provides a fastener which holds very firmly but is not likely to be separated by any accidental movement due to a particularly strong pull on the curtain in some direction, as is possible with 15 fasteners which open to one side wherein the jaws may be sprung so as to release or partially release the head. At the same time, when the user wishes he can readily separate the stud from the socket by tipping one 20 or the other sharply, as illustrated in Fig. 2 which action could hardly take place accidentally. It will be noted, furthermore, that this tipping may take place in any direction, because of the symmetrical structure 25 of the stud about its longitudinal axis and the symmetrical arrangement of the jaws. A fruitful source of vexation and annoyance in prior fasteners, wherein the operator had to experiment, pull and probably strain the fastener before he discovered 30 the correct direction of operation, is done away with.

While I have herein described in considerable detail the form of fastener shown and 35 described the operation thereof in specific words, it will be understood that I have done so in order that the theory and operation of the illustrative form disclosed might be more readily understood. The details of 40 structure might, of course, be considerably varied but what I claim and desire to secure by Letters Patent is:

1. A stud and socket fastener comprising 45 a centric group of jaws having co-planar arc-shaped portions and concentric flange portions substantially perpendicular thereto, said jaws collectively forming an interrupted cup, spring means for positioning the jaws and a headed stud adapted to enter the socket centrally between said jaws and having an abrupt shoulder inwardly 50 of the head behind which said arc-shaped portions are adapted to rest, said head being curved to engage the flange portions 55 when the elements of the fastener are relatively tipped whereby to spread the jaws.

2. In a stud and socket fastener a stud 60 having a shank and a head joined to said shank by an abrupt shoulder and a socket having a set of jaw members urged resiliently inward and collectively embracing the stud, said portions having angularly disposed parts adapted to lie respectively behind said shoulder and about the exterior 65 of the head, the head being curved to act

cam-like on the latter parts when the elements of the fastener are relatively tipped.

3. In a stud and socket fastener a stud having a shank and a head joined thereto by an abrupt annular shoulder, and a socket 70 having a symmetrical set of resiliently centripetal jaws having portions adapted to lie behind said shoulder, said fastener embodying in its construction a cam surface adapted to move one of said jaws outwardly 75 when the elements of the fastener are relatively tipped.

4. In a stud and socket fastener a stud having a shank and a head joined thereto by an abrupt annular shoulder, and a socket 80 having a symmetrical set of resiliently centripetal jaws having portions adapted to lie behind said shoulder, said fastener embodying in its construction a symmetrically arranged camming surface adapted to move 85 one or more of said jaws outwardly whenever the elements of the fastener are relatively sharply tipped.

5. In a stud and socket fastener, in combination, a headed stud and a socket having 90 a resiliently centripetal group of angular jaws, each having a flange arranged to lie inwardly beneath the head and a flange to lie exteriorly about the head.

6. In a stud and socket fastener, in combination, a socket having a jaw system comprising a divided annulus having an offset central portion forming a depression and a stud having a head formed in part closely to fit the depression and also formed with 100 a cam surface to spread the annulus when the elements of the fastener are relatively tipped.

7. In a stud and socket fastener, in combination, a socket having a jaw system comprising a divided annulus having an offset central portion forming a substantially cylindrical depression and a stud having a head formed with surfaces closely to fit the bottom and sides of the depression, said 110 surfaces being joined by a curved surface corresponding to the base angle of the cylinder, said head also having a cam surface to spread the annulus when the elements of the fastener are relatively tipped.

8. A stud and socket fastener comprising, in combination, a stud having a shank and a head joined to the shank by an annular shoulder having a part lying in a plane substantially perpendicular to the axis of the 120 shank, and a socket comprising a centric group of jaw members, each segmental in plan and angular in section and adapted to receive the outer circumference of said shoulder in the angle thereof and spring 125 means for positioning the jaws.

9. A fastener as defined in claim 8 wherein the segments fit together under constricting action of said spring means to form a complete annulus.

10. A fastener as defined in claim 8 where-
in the segments form each a third of a com-
plete annulus and fit together under con-
stricting action of said spring means.
- 5 11. In a stud and socket fastener a stud
having a shank and a head joined to said
shank by an abrupt shoulder and a socket hav-
ing resiliently centripetal jaws adapted to lie
behind said shoulder and interlock positively
10 therewith against direct outward pull, parts
associated with said jaws and arranged to
overlie the sides of the head, the latter be-
ing curved to act cam-like on said parts
when the elements of the fastener are rela-
tively tipped.
12. In a stud and socket fastener a stud
having a shank and a head joined to said
shank by an abrupt shoulder and a socket
20 having resiliently centripetal jaws adapted
to lie behind said shoulder and interlock
positively therewith against direct outward
movement, parts associated with said jaws
extending longitudinally of the stud, said
stud having a surface adapted to act cam-
like on said parts when the elements of the
25 fastener are relatively tipped.
13. In a stud and socket fastener a stud
having a shank and a head joined thereto
by an abrupt annular shoulder, and a socket
30 having a symmetrical set of resiliently cen-
tripetal jaws having portions adapted to
lie behind said shoulder, said fastener em-
bodying in its construction a cam surface
35 against which one or more of said jaws is
pressed whereby to disengage it or them
from the shoulder whenever the elements of
the fastener are relatively sharply tipped.
14. A stud-and-socket fastener comprising
a socket member composed of a casing hav-
40 ing a jaw-receiving chamber, jaws in said
chamber formed with locking flanges at
their inner edges, walls connecting said
flanges to the body portions of the jaws and
forming therewith a cylindrical cup, a
45 spring device for holding the jaw members
in their normal locking positions, and a
stud member formed with a head having a
square or perpendicular face at its inner
end, a rounded corner connecting said
50 square face with the body of the head, said
stud being reduced in diameter adjacent to
said face and having a cylindrical body part
of substantially the same diameter as the
head, and a curved cam-like part connecting
55 the reduced part with the cylindrical body
part.
15. A stud-and-socket fastener compris-
ing a socket member composed of a casing
having a jaw-receiving chamber, jaws in said
chamber formed with locking flanges at their 60
inner edges, walls connecting said flanges to
the body portions of the jaws and forming
therewith a cylindrical cup, a split ring en-
gaging the jaws and holding them in their
normal locking positions, and a stud member 65
formed with a head having a square or per-
pendicular face at its inner end, a rounded
corner connecting said square face with the
body of the head, said stud being reduced in
diameter adjacent to said shoulder, and hav-
70 ing a cylindrical body part of substantially
the same diameter as the head, and a curved
cam-like part connecting the reduced part
with the cylindrical body part.
16. A stud-and socket fastener comprising- 75
ing a socket member including a casing, an
annulus therein radially divided into three
or more parts, and spring means tending to
retain the truncated sectors so formed in
contact and comprising also a headed stud. 80
17. A stud and socket fastener comprising
a socket member including a casing, an
annulus therein radially divided into three
parts, and spring means tending to retain 85
the truncated sectors so formed in contact
and comprising also a headed stud member
adapted to enter said annulus.
18. A stud-and-socket fastener comprising
a socket member including a casing, an 90
annulus therein radially divided at three or
more points, and spring means tending to
retain the truncated sectors so formed in
contact and comprising also a stud member
formed with a shank, a head and a reduced 95
coaxial neck connecting said shank and
head, said shank merging smoothly into said
neck and said head being joined to said neck
by a square shoulder which at its exterior
periphery merges along a curved surface 100
into the outer surface of said head.
19. A stud-and-socket fastener comprising,
in combination, an apertured casing,
jaw members in said casing including seg-
mental members having concaved inner 105
edges presented adjacent the aperture and
fitting together to form an open frame or
annulus, constrictive spring means tending
to hold said members in contact, and a stud
member adapted to enter the aperture and 110
having a head to engage within said edges.

In testimony whereof, I have signed my
name to this specification.

DAVID BOURQUE.
